UNITED STATES PATENT OFFICE.

JOHN WILLIAM ZIMMERMAN, OF CHICAGO, ILLINOIS, ASSIGNOR TO ZIMMERMAN NOVELTY COMPANY, A CORPORATION OF ILLINOIS.

TOY.

1,080,670.

Specification of Letters Patent.

Patented Dec. 9, 1913.

Application filed March 14, 1912. Serial No. 683,660.

To all whom it may concern:

Be it known that I, JOHN W. ZIMMERMAN, a citizen of the United States, and a resident of Chicago, in the county of Cook and State 5 of Illinois, have invented certain Improvements in Toys, of which the following is a specification.

This invention relates to certain improvements in that variety of toys which are more 10 particularly designed and adapted for use by children for flipping or projecting pellets, such as beans, peas, and the like, and the object of the invention is to provide a device of this general character of a simple 15 and comparatively inexpensive nature, and of a strong and durable construction and which shall permit of such convenient and effective employment as will materially enhance the entertainment and amusement afforded by the device.

The invention consists in certain novel features of the construction, and combinations and arrangements of the several parts of the improved toy, whereby certain important 25 advantages are attained, and the device is rendered simpler, stronger and less expensive, and otherwise better adapted and more convenient for use, all as will be hereinafter fully set forth.

The novel features of the invention will be carefully defined in the claims.

In order that my improvements may be better understood I will now proceed to describe the same with reference to the accompanying drawings, wherein—

Figure 1 is a perspective view showing a toy embodying my improvements ready for use; Fig. 2 is a view similar to Fig. 1 with the parts in a different position; Fig. 3 is a 40 longitudinal transverse sectional view taken substantially central of Fig. 1 and on a somewhat enlarged scale; Fig. 4 is a view in rear elevation of the device; Fig. 5 is a perspective view illustrating a further embodiment of my improvements; and Fig. 6 is a longitudinal sectional view taken substantially central of Fig. 4.

Referring first to Figs. 1 to 4 inclusive, the improved device is therein illustrated as 50 formed with a body member 1 of elongated form, which may be conveniently made from a narrow strip of wood or the like, one end portion whereof as indicated at 2 in the drawings, is capable of being grasped with- 55 in the hand of the user, so as to afford a con-

venient handle by means of which the device is held during use. At the end opposite to the handle 2, the elongated body portion or member 1 is provided with the transverse recess or cavity 3 extending entirely across 60 the body portion or member and of substantially semi-circular configuration in cross section, the lower portion or wall of such cavity or recess, as indicated at 4, being inclined rearwardly, the rear of the device 65 being determined by the springs 5 and 6 to be hereinafter more particularly referred to. The springs 5 and 6 are herein shown as of the flat leaf type, and are superimposed one above the other, the lower ends of such 70 springs being angularly disposed, such angular portions being embedded within the elongated body portion or member 1, as indicated at 7, whereby such springs are effectually anchored or held by such portion or member 1. The free end portions of these springs intersect or obstruct the rear end of the recess or cavity 3 hereinbefore referred to, the innermost spring 5 having its free end terminating in substantially the 80 same plane as the upper end of the elongated body portion or member 1, while the outermost spring 6, as indicated at 8, projects a suitable or predetermined distance beyond the free end of the inner spring 5 in order that the same may be properly engaged by a finger of the user for the manipulation of the device, as will be more particularly set forth hereinafter. The recess or cavity 3 affords a chamber or container for the pellet 9 to be flipped or projected, such pellet being a bean, pea or the like, the incline of the lower portion or bottom wall 4 of such recess or cavity 3 serving to cause automatically 90 the pellet 9 by its own gravity to assume a position in contact with the inner spring 5. The spring 6, after being pulled away from the upper portion of the elongated body portion of the member 1 by the finger of the user, as shown in Fig. 1 of the drawings, 100 upon being released strikes or contacts with the inner spring 5 under its own resiliency with sufficient force to flip or project the pellet 9 to a considerable distance, and I have found that with slight practice the device may be employed to flip or project a pellet with great accuracy relative to the object desired. In order to relieve the anchoring point 7 of the springs 5 and 6 incident to the vibrations of the springs, when 110

the device is in use, I bridge or straddle said springs by the staple member 10, the prongs of such member 10 being firmly engaged with the body portion or member 1, while 5 the head thereof is in snug contact with the outermost spring 6, whereby such springs 5 and 6 are clamped against the body portion or member 1, so that the vibrations of the springs 5 and 6 at the points between 10 such member 10 and the anchoring point 7 is reduced to a minimum.

In the embodiment of my invention, contained in Figs. 4 to 6 inclusive, I employ an elongated body portion or member 11 15 formed from suitable metal, the upper end portion thereof being angularly disposed, as shown at 12, to afford a chamber or container 13, such angular portion 12 being bent substantially semi-circular in cross section in order that such chamber or container 20 may be produced. The member 11 is cut away as at 14, such cut away portion extending longitudinally of the angular portion 12 and downward a predetermined distance along the body portion 11 and this cut 25 away portion is adapted to accommodate the upper portion of a spring member 15, such member 15 having its lower end portion 16 angular and projecting within the cut away 30 portion 17. In order that this member 15 may be securely held to the body portion 11, I employ a staple member 18 bridging or straddling such member 15 as is clearly 35 shown in Figs. 5 and 6, for the purpose hereinbefore set forth with reference to the staple member 18, referred to with reference to Figs. 1, 2 and 3. The operation of this embodiment of my invention is thought to be obvious without a detail thereof.

40 From the foregoing description it will be seen that the improved toy constructed according to my invention is of an extremely simple and comparatively inexpensive nature, and is particularly well adapted for 45 use by reason of its strength and the con-

venience with which it may be manufactured and operated, and it will also be obvious from the above description that the toys are susceptible of some modification without material departure from the principles and spirit of the invention, and for this reason I do not desire to be understood as limiting myself to the precise formation and arrangement of the several parts as herein set forth in carrying out my invention in practice.

Having thus fully described my invention, what I now claim and desire to secure by Letters Patent is:—

1. A device of the character described 60 comprising a member having a chamber to accommodate a pellet, and a plurality of super-imposed springs secured to the member and having end portions intersecting the chamber.

2. A device of the character described 65 comprising a member having a chamber to accommodate a pellet, and a plurality of super-imposed springs secured to the member and having end portions intersecting the chamber, one of such springs being of greater length than the remainder.

3. A device of the character described 70 comprising an elongated member having a recess in one of its ends affording a chamber 75 to contain a pellet and a plurality of super-imposed springs, each of said springs having one end angular to the elongated member while the opposite end portions of such springs extend across the recess in the elongated member, one of such springs being of a greater extent than the other.

In witness whereof I have hereunto signed my name in the presence of two subscribing witnesses.

JOHN WILLIAM ZIMMERMAN
